(57) **CLAIM**

The ornamental design for a tissue cassette transport device, as shown and described.

DESCRIPTION

FIG. 1 is a perspective view of a tissue cassette transport device showing the claimed design;

FIG. 2 is a left side view thereof;

FIG. 3 is a right side view thereof;

FIG. 4 is a front side view thereof;

FIG. 5 is a back side view thereof;

FIG. 6 is a top view thereof;

FIG. 7 is a bottom view thereof; and,

FIG. 8 is an exploded perspective view thereof.

The broken lines shown in the figures illustrate portions of the tissue cassette transport device that form no part of the claimed design.
